UNITED STATES PATENT OFFICE.

BENZION KARFIOL, OF NEW YORK, N. Y.

DESIGN FOR A PAPER BELL.

45,636.

Specification for Design.

Patented Apr. 21, 1914.

Application filed January 10, 1914. Serial No. 811,473. Term of patent 7 years.

To all whom it may concern:

Be it known that I, BENZION KARFIOL, a citizen of the United States, residing at the city of New York, borough of Brooklyn, in the county of Kings and State of New York, have invented a new, original, and ornamental Design for Paper Bells, of which the following is a specification, reference being had to the accompanying drawing, forming part thereof.

The figure is a perspective view of a paper

bell having parallel horizontal stripes of various solid colors extending through the same, and illustrating my new design.

I claim:

The ornamental design for a paper bell, as shown.

BENZION KARFIOL.

Witnesses:

EDW. KARFIOL,
J. GRAAF.
